UNITED STATES PATENT OFFICE

WILLIAM CHARLES GARDINER, OF MANCHESTER, ENGLAND, ASSIGNOR TO F. REDDAWAY AND COMPANY, LIMITED, OF MANCHESTER, ENGLAND

WOVEN DRIVING BELTING

Application filed May 29, 1928, Serial No. 281,426, and in Great Britain June 18, 1927.

This invention relates to improvements in and in the manufacture of woven machine driving belts and the like and concerns the production of belting made partly from 5 warps of hair or wool, and cotton (or other vegetable fibre in lieu of cotton) and has for its object to produce thoroughly efficient belts using a comparatively small proportion of hair or wool warps relatively to those of cotton or other vegetable fibre employed in the 10 construction of the belt.

As is well known, hair has qualities extensile and contractile which make it an extremely valuable fibre for the production of 15 belting, but the cost of high grade material is several times that of cotton at this present time. Cotton yarn does not possess the elasticity, or power of recovery after elongation, of hair yarns and hence the known 20 cotton belting is not nearly so efficient as hair belting, particularly for heavy drives.

I seek to produce efficient belts from cotton or other vegetable yarns, and hair or wool yarns, woven and bound together in 25 plies or cloths, and with the cotton cloths forming the greater proportion, cotton being as stated so much cheaper.

I introduce into solid woven belting a strata, layer, or cloth, or ply, or more than 30 one of such, of hair yarns as warps, each warp end consisting of any number of separate threads which may be each of several strands and these threads may be twisted together or may be woven or run in parallel 35 to form bunches composing each a warp end of requisite diameter. These hair warp ends are so woven as to be as little crimped as possible, the cotton, or other weft (if such be used), interweaving with the hair warp 40 ends being passed under and over so that such weft suffers the major portion of the crimping or distortion. The object is to obtain the strata or layer of multiple thread hair warps or ends as straightly disposed as possible, and the hair warps or ends so constituted and disposed are woven into the 45 complete belting fabric under extra heavy tension. The separately working hair warp ends are for preference spaced at, say, double the pitch of the cotton warp ends in the sev-

eral cotton cloths thereby enabling heavy bunches of threads to be employed for each separately interweaving hair warp end. The resulting preponderance of hair warp diameter over cotton weft in the hair warp cloth 55 or layer enables the heavy hair warp ends to be substantially straight in that cloth or layer. The sets of warp ends forming the various cloths or layers, both cotton and hair, are taken from different warp beams where 60 required to allow each layer or cloth in the belt to be suitably tensioned, and the hair warp ends are woven at a high tension relatively to that of the cotton or like warps and preferably at a much higher tension than is 65 customary with the hair warps of hair belting of ordinary construction. This is done to develop the elasticity of the hair warps and to eliminate any permanent stretch which might otherwise take place due to the manner in which the hair yarns may have been 70 spun and/or twisted and for other reasons more fully explained later.

The hair warp cloth, layer, or strata, or 75 ply or plies, I preferably dispose in the centre of the complete belt or between the other layers, laminations, or cloths, or cotton or other vegetable fibre which combine with and embed or encase the hair warp strata, the whole succession of fabrics being bound together by a number of interconnecting warp 80 threads or binders as is known.

The invention is hereafter more particularly disclosed and ascertained, and, to assist the requisite detailed explanation the conventional diagrams on the accompanying 85 sheet of drawings can be referred to.

On the drawings:—

Fig. 1 shows in conventional fashion a 90 longitudinal section of a five cloth belt embodying the features of the invention, the figure being a broken length in a plane adjacent to one of the stout hair warps and showing weft cords in section.

Fig. 2 is a similar view in a plane adjacent to the next succeeding stout hair warp, the one figure being the complement of the other to properly render a longitudinal section.

Fig. 3 is a diagrammatic cross-section of 95 the belt (Figs. 1 and 2) through one trans-

verse plane, and is introduced to show that as far as possible the weft suffers the crimping rather than the stout hair warps which latter are shown in section in the middle.

Fig. 4 shows a longitudinal section of a modification wherein the stout hair warps are introduced as laterally abutting ends, all working similarly in the process of weaving, or as a hair warp layer sandwiched and bound between upper and lower cloths.

Fig. 5 is a diagram showing stout hair warp ends introduced as a layer forming the centre cloth of a multicloth driving belt, these hair warps being preferably of substantial proportions, bound by cotton or like weft and laid-in under much greater tension than the warps in the other superposed cotton or like cloths in accordance with my invention.

The Figs. 1, 2 and 3 indicate a preferred construction according to my invention and suggest a solid woven belt of five layers, cloths, or plies, it being understood the numbers and dispositions are capable of variations. The cloths are numbered 1, 2, 3, 4 and 5. In such a belt, the centre cloth is preferably the one in which the warp is of hair, each warp end *a* consisting of a suitable number of threads of a plurality of strands which threads may lie parallel with one another or be twisted together to form each individual hair warp end, each complete and separately working hair warp end being of, say $1\frac{1}{8}$ " diameter, or less or more, as may be convenient or desirable. These hair warp ends are interwoven with spaced cotton or other weft *b* with as little disturbance as possible of the hair warp ends *a* from the straight. The diagram Fig. 3, seeks to show that the cotton or like weft *b*, where same interconnects the hair warp ends *a*, is subjected to the crimping or puckering with the object of allowing the stout hair warps *a* to be kept as straight as possible.

On one face of the complete belt (which may be the non-driving face) lie the cloths of cotton or the like 4 and 5 preferably with warp ends *c*, *c'* each preferably composed of a number of fine stranded cotton threads say 5 or 6 (or more or less)—either running parallel or twisted together—in each group to lessen liability of stretch. In the diagrammatic Fig. 3 two ends are shown in each group, and each end may be supposed to consist of three threads. These cotton or like warp ends *c*, *c'* are woven together by the cotton or like weft *b*, the two cotton or like cloths 4 and 5 being combined in any known manner with the centre cloth 3 having the stout hair warps *a*. For the driving face I may provide the two cloths 1 and 2, the inner marked 2 of cotton or like warp ends *d* each composed of a number of fine yarns say 5 or 6 or more or less to each end either running parallel or twisted together

in each group for the purpose and as before related, the warp ends *d* interwoven by the cotton or like weft *b* of requisite thickness. For the outer or contact cloth 1 meeting the pulley face, this may consist of a cloth 1 with pile warp threads of cotton or the like (denoted by the letter *d'*) woven along with the lateral cotton or like weft *b*, to produce a warp pile or loop face for bedding to the pulley. Such pile or loop face is known and is no part of my invention. It is not essential, and the outer or other cotton or like cloths may be woven plain, or twill, or in other known manner. The tension on the cotton or like warps *c*, *c'*, *d*, *d'*, during weaving it is understood is not nearly so great as that on the stout hair warp yarns or ends *a*. The edges of the belt may be plain or any other type of woven edging may be arranged for in the weave.

It is to be understood that the indicated "five" cloth belt has its layers or combined fabrics all solid woven and bound together in the loom, say by cotton or other warp threads or binders similar to those marked *e* or according to any known scheme, and that tension of the woven-in straight hair warp cloth or layer is to a certain extent maintained after the belt leaves the loom by pressure from and contact with the superposed and woven therewith and combined and interconnected cotton cloths which lie thereover on each face and by the reluctance of same to shorten due to the character of the weave, as it will be understood the hair warp cloth or layer is embedded in the other cloths and positioned, encased, and protected from actual contact with the pulleys. Thus, the hair warp cloth forms an elastic core or extensible and contractile centre or layer (or more than one of such if multiples be desired) laid-up in the belt.

Consequently, whilst the outer cloths of cotton, which when the belt is at work, take the major part of the strain, would have little power of recovery after extension under load, the core or heart of the belt (consisting of the hair warp layer or strata) has a very considerable power of accommodation and can within narrow limits automatically re-compact the superposed cotton cloths. In this sense, when the belt is stretched and placed on the pulleys under tension, the elasticity of the belt is further developed to a slight percentage, rendered possible by reason of the presence of the hair cloth, and, when at work, the belt on the tight or driving stretch develops a tautness resulting in slight extension, which extension takes place on the tight or driving stretch in the running belt and is absorbed, due to the elasticity of the hair cloth or layer on the slack side or non-driving stretch, this extension and absorption being repeated during each cycle of rotation, all whereby the driving

qualities of a hair belt are obtained in a homogeneous cotton cased belt having little more than say for example about 20 per cent of hair or other suitable elastic animal fibre in its composition.

5 The layer or strata of stout hair warp ends *a* is woven into the belt under heavy tension for two reasons, in order (1) that the heavy warp ends of hair shall have their elasticity developed so that they immediately take a proper share of the load when the belt, having been stretched to a suitable initial tension on the pulleys, is put to work, and (2) to ensure that under any further stretch the belt 10 will always possess a contractile capacity exceeding the normal extensile liability of the belt as a whole when at work at loads even considerably in excess of normal practice, because the stout hair warps have developed 15 in them or possess an elasticity, or power of recovering, beyond the working stretch from time to time, all whereby a belt is produced which, by reason of the embedded stout hair warps, can recover on the slack side. In other 20 words under my invention the contractile capacity on the slack stretch is always sufficient to fully absorb the extension which may take place on the tight side or driving stretch, with the result that there is always a degree 25 of tension maintained in the slack stretch, even under the heaviest driving loads.

It is to be understood the number either 30 of hair warp cloths, or layers, or encasing vegetable fibre cloths is not material but five 35 cloths make a belt of acceptable thickness and strength for heavy drives such as require a belt of high transmitting capacity.

A belt properly constructed as related will 40 take and retain any of the known and approved fastening devices, and, when once properly tensioned and put into work, develops very little stretch and therefore rarely requires to be shortened or taken up.

45 Belts produced according to my invention are relatively inextensible under the working loads for which the belt is designed but are at all times capable of some slight extension on the tight side under heavy overload and yet possess the capability of contracting continuously on the slack stretch by reason of the embedded elastic hair layer or strata.

I may if desired although I do not consider this so good, simply place the heavy 50 warp ends of hair *a* one or more layers, in the belt, and under very heavy tension for the purposes already explained, as an encased strata or encased strata between the multiple cloths of cotton or like warp and weft and depend for the holding or disposing of such 55 hair warp ends on the pressure of the adjacent cotton layers due to the action of the known cotton or other binding or interconnecting warps such as *e* which tie the facing cloths or certain of them together in the complete solid woven belt. Such a scheme is

sufficiently indicated in diagrammatic fashion at Fig. 4. As a further modification, but one which is not considered so good, I might and preferably would use a set or sets of stout hair warps *a* in the centre or other 70 cloth, or these hair warps *a* may be of a diameter commonly employed in the weaving of ordinary hair belting the same being woven under very heavy tension as compared with the vegetable fibre warps in the superposed cloths, the whole being tied together by binder warps *e* to produce a solid woven multi-ply belt with a core or heart of stout or substantial hair warps woven in under heavy tension. This modification is clearly 75 suggested by the diagram Fig. 5.

The belts are preferably subjected to any of the well known treatments such as painting or impregnation after manufacture, together with the usual mechanical finishing 80 processes.

I declare that what I claim is:

1. A multi-ply woven belt comprising vegetable fibre plies and a ply composed of elastic hair warps laid in under relative tension sufficient to develop elasticity in the elastic hair warps, said hair warps being enclosed in the weaving as a stratum in extended condition and bound in by the weaving process, to maintain the stretched condition of the hair warps and produce an elastic core, whereby the belt has slight further extensile capacity, but has a balance of contractile power, the elastic hair warps functioning to develop a contractile capacity exceeding the extensile capacity.

2. A solid woven belt consisting of a number of encasing vegetable fibre cloths, and a ply of elastic animal fibre warps woven in with said cloths under heavy tension, the hair warps being interwoven by multi-thread vegetable fibre weft which serves for the other cloths, said cotton weft suffering the crimping, whereby a belt is produced with a stratum of stretched hair warp inherent in the weave of the belt, all said cloths being solid woven or bound together to maintain the stretched condition of the hair warps which are capable of extending and contracting.

3. A multi-ply woven belt consisting of a number of encasing vegetable fibre cloths, and a stratum with warps of elastic animal fibre woven in with said fibre cloths under heavy relative tension, the elastic animal warps being interwoven by multi-thread vegetable fibre weft which also serves for the other cloths, said vegetable fibre weft being subject to the crimping where same interweaves with the warps of elastic animal fibre, whereby a belt is produced with a stratum of stretched hair warp inherent in the weave of the multi-ply belt, all the cloths being solid woven or bound together to anchor the stretched condition of the warps of elastic

animal fibre, and which later are capable of extending and contracting.

4. A solid woven belt comprising upper and lower vegetable fibre plies, a ply comprising elastic hair warps laid in under considerable relative tension to develop the elasticity of said hair warps, said hair warps being enclosed in the weaving as a stratum and anchored in extended condition and bound by the weaving process, whereby an elastic hair fibre core is obtained, the belt having further extensile capacity and also contractile power when stretched, said elastic hair warps functioning to develop a contractile capacity exceeding the extensile capacity; and having multi-thread vegetable fibre weft serving the several cloths, and which tie all the cloths together, and warp binder threads which interconnect the whole of the plies.
